JOHN YOUNG.

UNITED STATES PATENT OFFICE.

JOHN YOUNG, OF CHILlicothe, OHIO.

PRESS.

1,246,371.

Specification of Letters Patent. Patented Nov. 13, 1917.

Application filed November 29, 1915. Serial No. 63,930.

To all whom it may concern:

Be it known that I, JOHN YOUNG, a citizen of the United States, residing at Chillicothe, in the county of Ross and State 5 of Ohio, have invented certain new and useful Improvements in Presses, of which the following is a specification.

My invention relates to presses of the type designed for use in obtaining unusually 10 heavy pressures as are used, for instance, in forming water marks in high grade writing paper. In this connection, my invention contemplates the provision of a press structure wherein a plurality of speeds may be had for 15 reciprocating the plunger or press head, the first of these speeds being somewhat rapid and the last very slow, but exceedingly powerful.

In this connection, one of the objects of 20 my invention resides in the provision of a plurality of screws upon the plunger or press head, these screws being operated by and having threaded connection with a suitable gear arrangement. It is also my object 25 to provide these screws with right and left hand threads, each screw carrying a suitable gear and a driving gear arranged to mesh with the gears on each set of right and left hand screws.

30 A further object of my invention resides in providing an extra weight structure arranged to come in opposition to the weight of the press head and its actuating mechanism to counterbalance the same. This structure is provided to more readily facilitate 35 the movement of the press head and its complementary structure from a lowered to an elevated position.

The preferred embodiment of my invention 40 is shown in the accompanying sheets of drawings, in which similar characters of reference designate corresponding parts, and in which:

Figure 1 is a side elevation of my press, 45 Fig. 2 is an end elevation looking toward the left in Fig. 1,

Fig. 3 is an end elevation looking toward the right of Fig. 1,

Fig. 4 is a top plan view of the structures 50 shown in Figs. 1, 2 and 3,

Fig. 5 is a transverse vertical section taken on line 5—5 of Fig. 1 and looking in the direction of the arrows,

Fig. 6 is a top plan view of the plunger or 55 press head mechanism shown removed from the remaining structure,

Fig. 7 is a section of one side of my press and taken on line 7—7 of Fig. 5, and,

Fig. 8 is a section, partially broken away, taken on line 8—8 of Fig. 5. 60

In the drawings, there is shown a general framework as comprising upstanding I-beams 1 forming the end walls of my press, these I-beams being rigidly connected together at their top and bottom ends by 65 means of two pairs of cross I-beams 2 and 3 respectively. These cross beams have all of their inside legs at their end portions cut out so that their central webs may lie flush against upstanding face plates 4 arranged to 70 lie against the bottom of the feet of the vertical I-beams 1. The vertical and cross beams are then bolted together, as shown at 5, these bolts also passing through the face plates 4, the nuts for these bolts bearing 75 against washer plates shown at 6. The press table is formed of a base plate 7 bolted directly to the lower cross beams 3, as is shown at 8, while the press head is formed of a plate 9 movable toward and away from the 80 press table 7 as will be described. By special reference to Fig. 7, it will be noted that the inside portions 10 of both upstanding beams 1 project slightly beyond the face plates 4 to 85 form trackways or guideways designed for coöperation with guide members 11 securely bolted to the press head 9, as shown at 12. This press head is then movable up and down and guided in this movement by means of the bearing members 11 coöperating with 90 the legs 10 of the beams 1. This upward and downward movement is effected mechanically by the provision of four vertically extending screws, those marked 13 having right hand threads, while those marked 95 14 are provided with left hand threads for a purpose to be presently described. These screws are attached to the press head by bolts 15 passing through foot extensions 16 at their base portions and are held in true 100 spaced relation at their upper ends by a plurality of spacing bars designated 29. The press head as a whole, is held in any position of adjustment by means of transverse plates 17 and 18, these two plates being 105 bolted together as shown at 19 and carrying between their adjacent surfaces suitable gears 20 and thrust bearings 21. All of the gears 20 have threaded connections with their respective screws 13 and 14 and further, 110 each pair of gears are designed and located so that they will be in mesh with each other,

but spaced from the adjacent set of gears. The two spaced sets are located apart distances permitting a working fit of the right and left hand worms 22 and 23 respectively, 5 it being noted that these worms are in mesh with opposite gears of each set and consequently rotation of these worms will impart rotation to both gears of both sets. These worms are rigidly mounted upon a 10 shaft 24 suitably journaled in the general framework of the press and carrying a pinion 25 on one end, this end being toward the left of Fig. 1. Coöperating with this pinion is a complementary gear 26 mounted upon 15 a stub shaft 27, this shaft also having rigidly connected therewith a hand wheel 28. On the opposite end of this shaft 24, there is loosely mounted a gear wheel having a suitable arrangement of external teeth 36 and a 20 suitable arrangement of concentric internal teeth 37, this latter being shown in Fig. 2. There is also mounted upon this end of the shaft 24, a spur pinion 38 rigidly carrying a hand wheel 39, this pinion being of a size 25 to have a working fit with the internal arrangement of teeth 37 and being further mounted upon the shaft by means of a keyed connection, thereby being rigid with respect to the shaft as far as its rotary movement is 30 concerned, but being slidable thereon longitudinally.

The operation of the device thus far described is as follows: Any rotary motion given to the shaft 24 by rotation of the 35 hand wheel 39, will cause rotation of the right and left hand worms 22 and 23. Since each set of worm wheels 20 are in mesh with each other, rotation of one will impart an opposite rotation to the other and consequently 40 the worm in mesh with this positively rotating worm wheel 20 must have opposite threads from that of the first named gear. Therefore, to provide a downward movement for opposite rotations of these 45 worm wheels, I have provided the right and left hand threaded screws 13 and 14. Also, to divide the pressure and strain more evenly throughout the surface of the press head, I have provided two sets of worms 20, this 50 latter set being in mesh with each other and one worm wheel of each set being in mesh with the same worm as shown particularly in Fig. 6. In order to obtain an upward or downward movement by this arrangement, 55 it is necessary that the screws on diagonally opposite corners be of the same thread arrangement or, in other words, the two screws on diagonally opposite corners must both be either right hand or left hand. Therefore, 60 rotation of the shaft 24 will cause a rapid up and downward movement of the press head as may be desired by means of the worm wheels and their screw connections.

In order that the amount of power required to move the press head up, will be

about the same as that required to move it down under no condition of load, I have provided a counterweight structure designed to counterbalance the effective weight of the press head and its actuating mechanism. 70 This counterbalance structure takes the form of two counterbalance weights designated 30 and slidable up and down in the channel formed between the leg portions 10 of the end beams 1. To the upper ends of these 75 counterweights, there are attached by means of the I-bolts 31, cables 32, these latter passing upwardly and over sheaves 33 suitably journaled in bearing members 34, these latter being located on the I-beams 1, at a 80 height slightly above the uppermost position of the press head itself. The opposite ends of these cables are shown as being attached at 35 to the upper edges of the press table itself and by this arrangement, these counterweights act in opposition to the normal weight of the press table and its actuating mechanism. 85

In order to obtain a second and slower speed and consequently a greater pressure 90 between the press table and press head by the same amount of applied power, I resort to the use of the hand wheel 28. Rotation of this hand wheel 28 imparts rotation to the gear wheel 26 and this latter imparts 95 rotation to the shaft 24 by means of the pinion 25. The rotation caused by this last connection will, however, be slower because of the gear reduction between the gears 25 and 26. 100

To give a third reduction in speed, I have mounted on the stub shaft 40 a combined spur pinion and worm wheel 41 so located that it will mesh with the external teeth on the gear 36 and also with the worm shown 105 at 42. This worm is mounted upon a shaft 43 carrying a hand wheel 44 at its outer extremity. Rotation of this last named hand wheel 44 will impart rotation to the worm wheel 42 and from there to the shaft 24 carrying the right and left hand worms 22 and 23 by means of the gear connections made by the combined spur pinion and worm wheel 41 and the gear wheel 36. In order to lock this gear wheel 36 to the shaft 24, it is necessary 110 that the pinion 38 and hand wheel 39 be moved to an innermost position in which the teeth on the pinion 38 engage the internal arrangement of teeth 37. 115

It will thus be apparent that I have provided a press in which a great amount of pressing power can be obtained by a simple manual operation. The arrangement of the screws 13 and 14 is such that the pressure will be evenly divided over the surface of 125 the press head and the weight of this press head will be counterbalanced by means of the counterweight structure 30.

What I claim, is:

1. In a press, a general framework whose 130

ends are formed of vertically arranged I-beams, a stationary press table, a movable press head guided in its up and down movement by the legs of said I-beams, and a counterweight structure slideable up and down in the channel space formed between said I-beams and said press table.

2. In a press, a general framework, a press table, a press head, a plurality of upstanding screws attached to said press head, a gear on each of said screws having threaded connection therewith and supported from said framework, a transverse shaft carried by said framework, worms on said shaft ar-

ranged to mesh with said gears, a hand wheel directly keyed to said shaft, a pinion on the opposite end of said shaft, a second gear meshing with said last named pinion, a hand wheel whereby said last named gear may be operated, a second pinion on said shaft, and a worm and worm wheel drive meshing with said last named gear.

In testimony whereof I affix my signature in presence of two witnesses.

JOHN YOUNG.
